(57) **CLAIM**

The ornamental design for an automotive wheel, as shown and described.

DESCRIPTION

FIG. 1 is a perspective view of an automotive wheel front face showing my new design; and,

FIG. 2 is a front elevational view thereof.

The broken lines shown in FIG. 1 illustrate portions of the automotive wheel that form no part of the claimed design. The stipple shading applied to the wheel in FIGS. 1 and 2 illustrate a contrast in appearance.
